UNITED STATES PATENT OFFICE.

STEPHEN PEMBER AND SAMUEL BIRD, OF WALPOLE, MASSACHUSETTS.

PAPER-MACHINE.

SPECIFICATION forming part of Letters Patent No. 285,838, dated October 2, 1883.

Application filed August 25, 1883. (No model.)

To all whom it may concern:

Be it known that we, STEPHEN PEMBER and SAMUEL BIRD, of Walpole, in the county of Norfolk, State of Massachusetts, have invented 5 a certain new and useful Improvement on Paper-Machines, of which the following is a description sufficiently full, clear, and exact to enable any person skilled in the art or science to which said invention appertains to make 10 and use the same, reference being had to the accompanying drawings, forming a part of this specification, in which—

Figure 1 is an isometrical perspective view; Fig. 2, a vertical transverse section, and Fig. 15 3 a view of the product of the machine.

Like letters of reference indicate corresponding parts in the different figures of the drawings.

Our invention relates to that class of machines which are employed in making laid paper; and it consists in a novel construction and arrangement of the parts, as hereinafter more fully set forth and claimed, by which a more effective article of this kind is produced 25 than is now in ordinary use.

In the drawings, A represents the body of the machine, B the exhaustion cylinder, and C the top roller. The cylinder is covered with wire-netting in the usual manner and journaled 30 horizontally in the pulp box or body A, the body, cylinder, and roller C being of the ordinary construction and arranged and used in the ordinary manner.

Mounted horizontally on the body A, and 35 standing at right angles to the axial line of the cylinder B, there is a shaft, D, carrying, respectively, at its outer ends the disk E and miter-gear G, the disk corresponding in diameter nearly with the width of the paper to be 40 produced. A short horizontally arranged shaft, H, carrying a fast and loose pulley, J, at its outer end and a small miter-gear, K, at its inner end, is also mounted in the body A, the shaft H being arranged at right angles to 45 the shaft D, and the gear K intermeshing with the gear G. Disposed on the shaft D there is also a disk, L, provided around its periphery with a series of spool-holding spindles, a, carrying the spools m, the spools being secured 50 on the spindles in any suitable manner, so as to rotate freely. The disk E is provided around

its periphery with a series of eyes or guides, d, corresponding in number and relative arrangement with the spools m.

An auxiliary roller, M, is disposed in the 55 body A, preferably in such a position as to be slightly submerged in the pulp liquid when the machine is in operation. This roller is arranged in parallelism with the cylinder B, against which it works and with which it co- 60 operates in making the paper. A spool, N, is placed near the disk L on either side of the body A, (but one being shown,) and from these spools the threads l are led into the machine over the roller M and embedded in the pulp 65 or paper in the same manner as the threads g. The threads l are designed to strengthen the fabric longitudinally and prevent it from being torn on the edge, and one or more may be employed on either side, as desired. 70

It will be obvious that either of the threads g, when followed through its course, will be found to be laid over the other threads g as it crosses the fabric in one direction and under them as it crosses in the opposite direction, 75 the rotation of the disks L E passing or laying the threads over each other in this manner.

We do not confine ourselves to the employment of any special number of threads g, or to running the disks in unison with the cylinder, 80 or in one direction only, as these may be varied without departing from the spirit of our invention; neither do we confine ourselves to the use of the edge threads, l, as they may be omitted entirely; or two or more may be 85 used in place of one on either edge, if desired.

In the use of our improvement the spools m are filled with the twine or thread to be used, the ends being carried through the guides d and inserted between the roller M and cylinder B in such a manner as to be equidistant from each other and distributed nearly the entire length of the roller. Power is then applied to the pulley f on the shaft of the cylinder B, and also to the pulley J on the shaft H, 90 the speed being such as to cause the disk L and cylinder B to rotate in unison, or nearly so. As the disks L E rotate, the threads g from the spools m are drawn into or through the machine between the roller M and cylinder B and 95 pressed into the film of pulp which is formed on the cylinder, in the usual manner, thereby 100

becoming embedded in and forming a part of the strip of paper *t*. The rotation of the disks *L* *E* causes the threads *g* to cross each other at *h*, so that the threads are laid diagonally across the strip or web of paper *t*, as best seen in Fig. 3, each thread crossing the web diagonally and being turned inwardly near its edge, and recrossing it, as best shown at *x* in Fig. 3, thereby greatly strengthening the fabric and affording a secure hold for tacks inserted in the bends *x* near the edge of the paper.

The paper or fabric, made as described, is designed more especially for use in the manufacture of carpet-linings, but is well adapted for many other purposes which will readily suggest themselves without particularizing; but as we propose to make the paper or fabric described, when in and of itself considered, the subject-matter of other Letters Patent, we do not herein claim the same, broadly.

Having thus explained our invention, what we claim is—

1. In a paper-making machine, the body *A*, cylinder *B*, and roller *M*, in combination with means, substantially such as described, for delivering the threads *g* to said cylinder and roller, substantially as set forth.

2. In a paper-making machine, the body *A*, cylinder *B*, and roller *M*, in combination with means, substantially such as described, for delivering the threads *g* and threads *l* to said cylinder and roller, substantially as specified.

3. In a paper-making machine, the body *A*, cylinder *B*, and roller *M*, in combination with

means, substantially such as described, for delivering the threads *g* to said cylinder and roller and crossing and recrossing said threads in the paper or fabric, substantially as set forth.

4. In a paper-making machine, the body *A*, cylinder *B*, and roller *M*, in combination with means, substantially such as described, for delivering the threads *g* to said cylinder and roller and crossing and recrossing said threads, and with means for delivering the threads *l* to said cylinder and roller in such manner that they will be embedded in the edges of the paper or fabric, substantially as specified.

5. In a paper-making machine, the body *A*, cylinder *B*, and roller *M*, in combination with the disk *L*, provided with the spools *m*, the disk *E*, provided with the guides *d* and shaft *D*, combined and arranged to operate substantially as set forth.

6. In a paper-making machine, the shaft *D*, carrying the spool-disk *L*, guide-disk *E*, and gear *G*, in combination with the gear *K*, shaft *H*, pulley *J*, cylinder *B*, roller *M*, and body *A*, substantially as shown and described.

7. In a paper-making machine, the shaft *D*, carrying the spool-disk *L*, guide-disk *E*, and gear *G*, in combination with the gear *K*, shaft *H*, pulley *J*, cylinder *B*, roller *M*, spools *N*, and body *A*, substantially as set forth.

STEPHEN PEMBER.
SAMUEL BIRD.
